(57) **CLAIM**

The ornamental design for a wearable remote fob protector, as shown and described.

DESCRIPTION

FIG. 1 is a top perspective view of the first embodiment of the wearable remote fob protector.

FIG. 2 is a bottom perspective view of the first embodiment of the wearable remote fob protector.

FIG. 3 is a right side elevation view of the first embodiment of the wearable remote fob protector.

FIG. 4 is a front elevation view of the first embodiment of the wearable remote fob protector.

FIG. 5 is a left side elevation view of the first embodiment of the wearable remote fob protector.

FIG. 6 is a rear elevation view of the first embodiment of the wearable remote fob protector.

FIG. 7 is a top plan view of the first embodiment of the wearable remote fob protector.

FIG. 8 is a bottom plan view of the first embodiment of the wearable remote fob protector.

FIG. 9 is a top perspective view of the second embodiment of the wearable remote fob protector.

FIG. 10 is a bottom perspective view of the second embodiment of the wearable remote fob protector.

FIG. 11 is a right side elevation view of the second embodiment of the wearable remote fob protector.

FIG. 12 is a front elevation view of the second embodiment of the wearable remote fob protector.

FIG. 13 is a left side elevation view of the second embodiment of the wearable remote fob protector.

FIG. 14 is a rear elevation view of the second embodiment of the wearable remote fob protector.

FIG. 15 is a top plan view of the second embodiment of the wearable remote fob protector.

FIG. 16 is a bottom plan view of the second embodiment of the wearable remote fob protector.

FIG. 17 is a top perspective view of the third embodiment of the wearable remote fob protector.

FIG. 18 is a bottom perspective view of the third embodiment of the wearable remote fob protector.

FIG. 19 is a right side elevation view of the third embodiment of the wearable remote fob protector.

FIG. 20 is a front elevation view of the third embodiment of the wearable remote fob protector.

FIG. 21 is a left side elevation view of the third embodiment of the wearable remote fob protector.

FIG. 22 is a rear elevation view of the third embodiment of the wearable remote fob protector.

(Continued)

FIG. 23 is a top plan view of the third embodiment of the wearable remote fob protector.

FIG. 24 is a bottom plan view of the third embodiment of the wearable remote fob protector.

FIG. 25 is a top perspective view of the forth embodiment of the wearable remote fob protector.

FIG. 26 is a bottom perspective view of the forth embodiment of the wearable remote fob protector.

FIG. 27 is a right side elevation view of the forth embodiment of the wearable remote fob protector.

FIG. 28 is a front elevation view of the forth embodiment of the wearable remote fob protector.

FIG. 29 is a left side elevation view of the forth embodiment of the wearable remote fob protector.

FIG. 30 is a rear elevation view of the forth embodiment of the wearable remote fob protector.

FIG. 31 is a top plan view of the forth embodiment of the wearable remote fob protector.

FIG. 32 is a bottom plan view of the forth embodiment of the wearable remote fob protector.

FIG. 33 is a top perspective view of the fifth embodiment of the wearable remote fob protector.

FIG. 34 is a bottom perspective view of the fifth embodiment of the wearable remote fob protector.

FIG. 35 is a right side elevation view of the fifth embodiment of the wearable remote fob protector.

FIG. 36 is a front elevation view of the fifth embodiment of the wearable remote fob protector.

FIG. 37 is a left side elevation view of the fifth embodiment of the wearable remote fob protector.

FIG. 38 is a rear elevation view of the fifth embodiment of the wearable remote fob protector.

FIG. 39 is a top plan view of the fifth embodiment of the wearable remote fob protector.

FIG. 40 is a bottom plan view of the fifth embodiment of the wearable remote fob protector.

FIG. 41 is a top perspective view of the sixth embodiment of the wearable remote fob protector.

FIG. 42 is a bottom perspective view of the sixth embodiment of the wearable remote fob protector.

FIG. 43 is a right side elevation view of the sixth embodiment of the wearable remote fob protector.

FIG. 44 is a front elevation view of the sixth embodiment of the wearable remote fob protector.

FIG. 45 is a left side elevation view of the sixth embodiment of the wearable remote fob protector.

FIG. 46 is a rear elevation view of the sixth embodiment of the wearable remote fob protector.

FIG. 47 is a top plan view of the sixth embodiment of the wearable remote fob protector; and,

FIG. 48 is a bottom plan view of the sixth embodiment of the wearable remote fob protector.

The broken lines illustrate environmental matter that form no part of the claimed design.
